ALEXANDRE F. GODEFROY, OF LOS ANGELES, CALIFORNIA

HAIR CURLING APPARATUS

Application filed January 13, 1931. Serial No. 508,417.

This invention relates to a new apparatus and method for permanently curling and waving hair.

An object of the invention is to provide means whereby hair may be more quickly and satisfactorily curled or formed into permanent waves than has heretofore been possible.

Another object of the invention is to provide, as a new article of manufacture, an attachment for curling irons now in use which may be employed in conjunction with such curling irons to expedite the work of a hair dresser or operator of the beauty parlor in forming curls or permanent waves in the hair.

A further object of the invention is to provide means whereby the heat for curling the hair may be applied thereto in a more effective manner so that the work will be more efficiently and satisfactorily done.

Referring to the accompanying drawings which illustrate what is at present deemed to be a preferred embodiment of the invention,

Fig. 1 of the drawings is a side elevation, slightly in perspective of a pair of curling irons having the attachment mounted thereon.

Fig. 2 is an end view of Fig. 1, the curling iron being in the closed condition.

Fig. 3 is an end view of Fig. 2 the curling irons having been withdrawn but the attachment having been slipped therefrom and being shown embedded in a whirl of the hair.

Fig. 4 is a partial side view of the head of the subject showing the curling attachment in place within the hair during the curling operation, the electric circuit being partially in diagram.

Referring in detail to the drawings, Fig. 1 shows a pair of curling irons provided with the usual concavo-convex jaws 7 and 8 which are pivotally secured together at 9 and which are operated by the usual handle members 10. The attachment for said jaws which is provided by this invention, consists of the elongated concavo-convex plates 11 and 12, said plates being adapted to fit over the convex side 50 of the jaws 7 and 8 as shown in the drawings.

Each of these plates is provided with a pair of front clips 15 and a pair of rear clips 16, these clips being adapted to engage the inner edged portions of the jaws of the curling irons as shown. By means of said clips each of the elongated plates 11 is slidably attached to the curling irons.

Each of the concavo-convex plates 11 is constructed as electrically heated members of the resistance type, on the same general principle as electrically heated implements, the detail construction of the electric heating features not being shown in drawings, for the reason that, separately considered, they form no part of the present invention.

The inner end of each of the heating plates is shown provided with a conducting wire 20 and the outer end with a conducting wire 21. The said wires being respectively detachably connected to the plate in any well known manner as by the terminal devices 22 and 23.

In Fig. 2 the appearance of the curling irons with the curling plates mounted upon them is shown as these parts appear after the tool has been inserted into the hair of the subject and then rotated several times thus forming a curl 30 of hair around them as indicated in dotted lines in this view. In Fig. 3 are shown only the curling plates 11 and 12, the curling iron having been withdrawn from said plates leaving said plates embedded in a curl of hair 30.

In Fig. 4 are shown a number of curl clumps of hair 30, the curling plates being embedded within the curls of hair shown, and by means of the wires 35 and 36 being connected with a source of electric supply for the purpose of supplying additional heat to the curled hair to add to the permanency of the curling operation.

In the operation of the apparatus the curling plates 11 and 12 are detachably mounted upon the jaws of the curling iron as shown in Fig. 1. The wires 20 and 21 are connected electrically with each of said plates. After this has been done electric current is supplied from any suitable source (not shown) until said plates become sufficiently heated to perform properly the curling operation. The wires 20 and 21 are then detached from each

of the concavo-convex plates and the tool is then ready for use. While the plates 11 and 12 are still hot the tool is thrust into the hair and rotated in the usual manner thus winding the hair upon the jaws of the tool and upon the plates 11 and 12 mounted thereon.

If desired, several pairs of curling tongs may simultaneously have the curling plates mounted thereon and said curling plates then 10 electrically heated in the manner stated. After each curling iron has been thrust into the hair, together with the heated plates and rotated to curl the hair thereon, then the curling iron is withdrawn from the concavo-convex curling plates, said plates being thus left 16 embedded with a pair of the plates within each curled portion of the hair as shown in Fig. 3. Finally, after the desired number of the paired curling plates have been embedded 22 in the hair, as shown in Fig. 4, the wires 20 and 21 may again be connected up with the plates and the plates again heated to render the curling of the hair more permanent.

By heating the concavo-convex curling 25 plates in the hair and after the jaws of the curling irons have been withdrawn from them, a smaller amount of metal requires to be electrically heated than it would be necessary to heat electrically if the jaws of the 30 curling irons were heated while the curling plates were mounted on them. Furthermore, the heating of a considerable number of concavo-convex curling plates while all these 35 plates are in place in the hair can be quickly and effectively attended to, which would be very difficult if the curling irons were not withdrawn from the curling plates before the latter were heated electrically.

Claims:

40. 1. The combination, with a pair of curling irons having jaws pivotally related to each other, of a curling plate having a sliding fit upon a jaw of said curling irons, whereby said curling plate may, by said curling irons, have the hair of a human subject coiled therearound, and means unaffected by the relative 45 positions of said jaw and plate to supply electric current to said plate to heat the same in the hair.
50. 2. The combination, with a pair of curling irons having jaws pivotally related to each other, of a concavo-convex curling plate having a sliding fit upon a jaw of said curling irons, whereby said curling plate may, by said 55 curling irons, have the hair of a human subject coiled therearound, and means unaffected by the relative positions of said jaw and plate to supply electric current to said plate to heat the same in the hair.
60. 3. The combination, with a pair of curling irons having jaws pivotally related to each other, of an elongated concavo-convex curling plate fitting slidably upon each of said jaws and slidably removable therefrom in an end- 65 wise manner, and means unaffected by the po-

sitions of said plates with relation to said jaws to electrically heat said plates after the jaws of the curling irons have been withdrawn from said plates.

In testimony whereof I hereunto affix my 70 signature.

ALEXANDRE F. GODEFROY.
